United States Patent Office

Des. 207,575
Patented May 2, 1967

207,575

LAWN SPRINKLER

John D. Beinert, Babylon, N.Y., assignor to International Patent Research Corp., 1/2 Milton Friedman, New York, N.Y., a corporation of New York

Filed Aug. 11, 1966, Ser. No. 3,430

Term of patent 7 years

(Cl. D91—1)

FIG. 3

FIG. 4

FIG. 7

FIG. 5

FIG. 6

FIG. 1 is a side elevational view of a lawn sprinkler showing my new design;

FIG. 2 is a top plan view of the sprinkler of FIG. 1;

FIG. 3 is a bottom plan view of the sprinkler of FIG. 1;

FIG. 4 is an end elevational view taken from the left hand side of FIG. 1;

FIG. 5 is an end elevational view taken from the right hand side of FIG. 1; and

FIGS. 6 and 7 are end elevational views taken along the lines 6—6 and 7—7 respectively of FIG. 1.

The dominant portions of my design are shown in solid lines.

I claim:

The ornamental design for a lawn sprinkler, as shown and described.
